GAETANO FORMICA, OF NEW YORK, N. Y.

Letters Patent No. 89,924, dated May 11, 1869.

IMPROVED ROCKING-CHAIR.

The Schedule referred to in these Letters Patent and making part of the same.

To all whom it may concern:

Be it known that I, GAETANO FORMICA, of the city, county, and State of New York, have invented a new and useful Improvement in Rocking-Chairs; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved rocking-chair.

Figure 2 is a detail sectional side view of the same.

Figure 3 is a detail transverse section of the same.

Similar letters of reference indicate corresponding parts.

This invention relates to a rocking-chair of that class in which the seat is pivoted to a supporting-frame, and held in front and rear by a spring or springs.

The invention consists in connecting the apparatus with a rotary fan on the back of the chair, so that said fan will be set in motion and revolved whenever the chair is rocked in its support.

A, in the drawing, represents the support of the chair.

B is one side bar of the chair-seat; C, the other.

These side bars are connected by suitable cross-bars *a*, and by a bottom of suitable construction, and carry also the side pieces of the chair-back D, as shown.

The seat is, by means of a pin, *b*, passing through lugs *c* of the seat into a projection, *d*, of the support, or otherwise, pivoted to the latter, and can be oscillated on the pin *b*, or its equivalent.

A spring or springs, *e*, acting in front and rear of the pivot, against the under side of the seat, give to the rocking motion the requisite elasticity.

For this purpose a simple flat spring, *e'*, may be employed, which is fastened to the projection *d* of the

support, and reaches forward and backward of the same.

To each side bar of the seat is pivoted a lever, *E*, which is, by a rod, *f*, connected with the crank-axle *g* of a rotary fan, *F*, that has its bearings in arms projecting forward from the upper part of the chair-back.

The pivot *h* of the lever *E*, on the bar *B*, is at the middle of the lever, as in fig. 1, so that a pin, *i*, on the front end of said lever, will come under one of the springs *e*.

The pivot of the lever *E* of the bar *C*, is, as in fig. 2, on the front end of the same, so that the pin *i* will be near the middle of the same.

The two levers will thus, as the chair is rocked on the pin *b*, swing on their centres *h*, in opposite directions, one moving up when the other goes down; thus the requisite rotary motion is imparted to the fan by the oscillating motion of the chair.

Having thus described my invention,

What I claim as new, and desire to secure by Letters Patent, is—

1. The levers *E* *E*, pivoted to the side bars of the swinging seat, and connected with the rotary fan, as described, they being so hung that they will swing in opposite directions, substantially as herein shewn and described.

2. The combination of the support *A*, which carries the pivoted seat, with the springs *e*, levers *E*, rods *f*, and rotary fan *F*, all arranged and operating substantially as herein shown and described.

The above specification of my invention signed by me, this 24th day of March, 1869.

GAETANO FORMICA.
